(57) CLAIM

The ornamental design for a bottle, as shown and described.

DESCRIPTION

FIG. 1 is a front, top, right perspective view of the bottle of my new design, shown without the broken line showing of the unclaimed cap to expose the unclaimed pour spout and threads;

FIG. 2 is a front elevational view thereof, the rear elevational view being a mirror image;

FIG. 3 is a right side elevational view thereof; the left side elevational view being a mirror image;

FIG. 4 is a top plan view thereof;

FIG. 5 is a bottom plan view thereof; and,

FIG. 6 is the front, top, right perspective view of FIG. 1 shown with the unclaimed cap.

The broken line showing in the drawings is for illustrative purposes only and forms no part of the claimed design.
